[57] CLAIM

The ornamental design for a half round hardie, as shown and described.

DESCRIPTION

FIG. 1 is an isometric view taken from the top, front and side of a half round hardie showing my new design;

FIG. 2 is a rear view thereof;

FIG. 3 is a front view thereof;

FIG. 4 is a side view thereof, the opposite side being a mirror image;

FIG. 5 is a top view thereof;

FIG. 6 is a bottom view thereof.
